O. M. EASTWOOD

CLOTHES DRIER

Filed Nov. 4, 1924

O.M. Eastwood
By Watson E. Coleman
Attorney

UNITED STATES PATENT OFFICE.

ORDELLIA M. EASTWOOD, OF SYLACAUGA, ALABAMA.

CLOTHES DRIER.

Application filed November 4, 1924. Serial No. 747,815.

To all whom it may concern:

Be it known that I, ORDELLIA M. EASTWOOD, a citizen of the United States, residing at Sylacauga, in the county of Talladega and State of Alabama, have invented certain new and useful Improvements in Clothes Driers, of which the following is a specification, reference being had to the accompanying drawings.

10 This invention relates to certain improvements in clothes driers and it is an object of the invention to provide a novel and improved device of this general character constructed in a manner whereby the same will 15 occupy a minimum of space when not in use and which may also be moved from one place to another as may be required.

Another object of the invention is to 20 provide a novel and improved device of this general character comprising garment supporting fingers or arms mounted for swinging movement in a vertical direction together with means for maintaining said arms or fingers in an extended position for 25 use.

The invention consists in the details of construction and in the combination and arrangement of the several parts of my improved clothes drier whereby certain important advantages are attained and the device rendered simpler, less expensive and otherwise more convenient and advantageous for use, as will be hereinafter more fully set forth.

30 35 The novel features of my invention will hereinafter be definitely claimed.

In order that my invention may be the better understood, I will now proceed to describe the same with reference to the accompanying drawings, wherein:—

Figure 1 is a view in front elevation illustrating a clothes drier constructed in accordance with an embodiment of my invention;

40 45 Figure 2 is a sectional view taken substantially on the line 2—2 of Figure 1;

Figure 3 is a fragmentary view in perspective illustrating the pivoted end portion of a finger or arm having a connecting rod associated therewith.

50 55 As disclosed in the accompanying drawings, my improved drier comprises a pair of upstanding posts 1 connected at points spaced lengthwise thereof by the rods 2. Each of the rods 2 has its extremities directed through a post 1 with the holding

nuts threaded thereon and contacting with the post at opposite sides thereof.

The lower end of each of the posts 1 is secured to the central portion of a base member or sill 3 and associated with said base member or sill 3 and the coating post 1 are the brace members 4. Each of the base members or sills 3 is preferably provided with the rollers 5 or the like whereby the device in its entirety may be readily and conveniently moved from one place to another as required. Each of the rods 2 has pivotally engaged therewith for free swinging movement in a vertical direction 70 the fingers or arms 6, said fingers or arms 6 being alternately disposed in opposite directions. Each series of similarly directed fingers or arms 6 adjacent their pivoted end portions are tied or connected by the rod 8 75 whereby said fingers or arms are maintained substantially in parallel relation and for unitary swinging movement in the same direction.

The post 1 adjacent the extremities of 80 each of the rods 2 and slightly therebelow is provided with the outstanding and oppositely directed arms 9 having their upper edges notched, as at 10, to receive the extremities 85 of a bar 11. A bar 11 is adapted to be supported by the required arms 9 below a raised or extended series of fingers or arms 6 so that said series of fingers or arms will be effectively maintained in extended position 90 to permit the requisite engagement therewith of clothing or other articles to be dried.

When the device is not in use the bars 11 are removed whereby the fingers or arms 6 may readily swing downwardly into substantially a vertical depending position so that the device in its entirety will occupy a minimum of space and which is of particular importance when the device is being moved from one place to another, more especially through a doorway.

From the foregoing description it is thought to be obvious that a clothes drier constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting

myself to the precise arrangement and formation of the several parts herein shown in carrying out my invention in practice except as hereinafter claimed.

5 I claim:—

1. A clothes drier comprising a pair of upstanding posts, a rod connecting said posts, fingers pivotally engaged with said rod, said fingers being arranged into two 10 series, one series being adapted to extend beyond one side of the device, the second series extending beyond the opposite side of the device, means for connecting the fingers of each series for unitary movement, and 15 means for holding each series of fingers, when raised, against downward movement.
2. A clothes drier comprising a pair of

upstanding posts, a rod connecting said posts, fingers pivotally engaged with said rod, said fingers being arranged into two 20 series, one series being adapted to extend beyond one side of the device, the second series extending beyond the opposite side of the device, means for connecting the fingers of each series for unitary movement, oppositely directed arms carried by the posts adjacent to the rod, and bars adapted to be supported by said arms and positioned below the series of fingers when raised to hold said series of fingers against downward 25 movement.

In testimony whereof I hereunto affix my signature.

Mrs. ORDELLIA M. EASTWOOD.
